UNITED STATES PATENT OFFICE.

JOSEPH H. GINET, OF DENVER, COLORADO.

APPARATUS FOR TREATING BITUMINOUS SHALE AND THE LIKE.

Application filed November 1, 1920. Serial No. 421,111.

To all whom it may concern:

Be it known that I, JOSEPH H. GINET, a citizen of the United States, residing at Denver, in the county of Denver and State of Colorado, have invented certain new and useful Improvements in Apparatus for Treating Bituminous Shale and the like; and I do hereby declare the following to be a full, clear, and exact description of the invention, such as will enable others skilled in the art to which it appertains to make and use the same.

This invention relates to apparatus for treating bituminous shales, commonly known as oil shales.

An object of this invention is to provide means for so moving the shale in a furnace or retort that every particle of shale in any given section or zone of the furnace shall be subjected to substantially the same heat at substantially the same time.

A further object of this invention is to provide in a shale furnace or retort improved shale agitating means adapted to lift and shower the shale so that each particle is exposed to the heat of the retort and the entire mass of shale may be evenly heated.

A further object of this invention is to provide in a shale furnace or retort improved shale conveying means.

A further object of this invention is to provide in a shale furnace or retort improved means for dividing or separating the furnace into zones or sections.

A further object of this invention is to provide in a shale furnace or retort improved combined shale conveying and agitating means.

A further object of this invention is to provide an apparatus whereby my improved process of treating shale as fully disclosed and set forth in my pending application Serial No. 334,840, filed October 31st, 1919, may be advantageously carried out.

With these and other objects in view, the invention consists in the construction, combination, arrangement and detail of parts as hereinafter more fully described and claimed.

Two sheets of drawings accompany this specification as part thereof, in which like

reference characters denote like parts throughout.

Figure 1 is a vertical longitudinal view partly in section taken on the line 1—1 of Figure 2.

Figure 2 is a vertical transverse section through a retort.

Figure 3 is a bottom view of the improved shovel showing the pivotal support.

Figure 4 is a plan view of the improved shovel.

Figures 5 and 7 are detail views of two types of bottom formation for the shovel.

Figure 6 is a sectional view taken on the line 6—6 of Figure 5.

Bituminous shales contain organic matter which, when the shale is heated volatilizes and passes off as hydrocarbon gases. Different hydrocarbon gases pass off at different temperatures. At the lowest temperature there will be evolved the gas from which the lightest oil, such as gasoline, etc., may be obtained by condensation.

At successively higher temperatures there will be successively evolved the various gases from which respectively there may be obtained by condensation successively heavier oils.

If, at any time, or any stage of the process any portion of the shale be subjected to a substantially higher temperature than that at which the lightest gas still contained in the shale is evolved, fixed gases and unsaturated gases will be formed and likewise any gas evolved at the lower temperature will, by subjection to the higher temperature, be changed to fixed gas and unsaturated gas, resulting in loss in both quantity and quality of oils.

Therefore, in recovering oils from shale it is desirable to subject the shale to successively increasing temperatures and at each stage of the treatment to subject it to the lowest temperature at which any substantial quantity of hydrocarbon gas will be evolved therefrom and to hold the shale at such temperature until there has been evolved therefrom all of the gas that can be evolved at that temperature and it is likewise evidently desirable that all of such gas be drawn off, while still at substantially that temperature, for condensation.

The uniform heating of all of the shale in each stage or zone of the treatment is essential and likewise the free escape of the gas as it is evolved, is essential. An uneven 5 heating of the shale and compelling the evolved gas to pass through the mass of shale as it escapes, will result in premature condensation of gas and also in coking and fluxing the shale thus losing values and rendering the shale impossible of efficient treatment.

The principal element of my present invention is an apparatus for treating shale in which the shale is so moved, showered, 15 sprayed or agitated that the heat is given free access to each particle of shale and gas is permitted to freely escape from each particle without having to pass through the shale mass and this is accomplished while 20 and in combination with moving large quantities of shale through the furnace or retort in which the treatment takes place.

My apparatus is more particularly described as follows:

25 I provide a shell 1, housing 2 spaced therefrom as at 3 and supported therein as at 4. Any suitable heating means, preferably a zone furnace as 5, may be employed for providing successively increasing heat at the various sections or zones of the shell 1. Any suitable means, as hopper 6, may be employed for feeding fresh shale into one end of the shell, the spent shale being discharged at the opposite end through any suitable discharge 35 means, indicated at 7. A suitable vent for products of combustion from the heating means may be provided, as indicated at 8.

At predetermined desirable points along 40 the shell, vents, as 9, are provided for drawing off the evolved hydro-carbon gases.

Within the shell 1 is positioned a shaft 10 extending through and suitably revolvably mounted and packed in the ends of the shell as at 11, which shaft may be revolved by any 45 suitable means, as indicated by the crank 12. Upon the shaft 10 I mount and attach in any suitable manner, as by collar 13 and set screws 14, suitable arms 15—15, preferably 50 formed integral, as shown, for carrying shovels 17 for lifting, and dropping in a loose manner or spraying or showering and advancing the shale through the retort, as will be hereinafter more particularly described.

55 The shovels 17 are formed with side guides 18—18 extending not quite the full length of the bottom 19. At the rear end of one guide an extension 20 is hinged, as at 21, and means, such as holes 22, in the bottom of the shovel and perforated offsets 23 secured to the extension guide are provided for securing this extension guide in various angular positions, as indicated in 60 Figure 4. Any ordinary bolt (not shown) 65 passed through hole 22 in the bottom and

perforated lug 23 will secure the extension 70 20, as desired. The shovel 17 is supported by a member 24, having downturned lugs 25, by means of which and a bolt 27 the shovel is pivotally supported to the arms 15 below 75 and back of its center of gravity. By means of this structure, as indicated in Figure 2, the forward edge of the shovel uniformly scrapes the lower portion of the wall of the retort by operation of gravity aided by 80 centrifugal force. This structure further permits the tilting back of the shovel in case it should strike any unusual obstruction.

The shovels, as thus described, are mounted on shaft 10 with an angular variation 85 between the shovels in each succeeding pair and so that the shovels of succeeding pairs are closely adjacent, as indicated in Figure 1. It will be apparent that the shale 90 picked up by each shovel will be forced up and over its inclined bottom and dropped onto the floor of the retort and that the shale, in dropping from each shovel will be directed by the guide 20 thereon toward and more or less of it (according to the adjustment of the guide) into the path of the adjacent pair of shovels and by arranging 95 all of the guides 20 on the same side of their respective shovels. This operation will be 100 repeated continuously and successively by each of the various shovels, thus conveying the shale from one end of the retort to the other.

105 Through the operation of shovels 17 the shale is lifted from the floor of the retort and sprinkled or showered or dropped in loose manner from the back end of the shovel onto the floor of the retort again and at each operation the position of the particles of shale is changed, both in relation to each other and in relation to the floor of the retort so that new and different portions of the shale are successively brought into contact with the floor of the retort.

110 To still more effectively shower and mix the shale, the bottom 19 of the shovel may have parts 26—26' struck up therefrom at an inclination, thus leaving openings 26'' in the bottom. Portions of the shale, in passing along the bottom 19 will, obviously drop through these openings so that the shale will shower or spray down, not only from the rear end of the shovel, but at various points throughout its area. Much of the 115 shale which does not drop through the openings 26'' will encounter the upraised portions 26—26' and be retarded thereby while other portions will not be retarded. Thus a more thorough mixing of the shale passing 120 over the shovel is accomplished.

125 It will thus be apparent that by the novel structure and arrangement of shovels 17 the shale is lifted, showered, mixed and advanced within and through the retort with substantial continuity. It will be obvious 130

that the adjustable side guide extensions 20 may be set at different angles on the different shovels and that by so doing the speed of advancement of the shale may be controlled 5 and varied at different points along the retort. It will also be obvious that the shovels may be rotated at considerable speed without any mechanical difficulties in the retort construction and the shale can, if desired, 10 be kept in practically a constant state of spray or suspension within the retort. Another very important advantage of the present structure is that by means of it there is no mounding of the shale upon the floor of 15 the retort, such as is necessarily found with screw conveyers, and all the resulting difficulties due to uneven heating of the shale and obstruction to the escape of gas therefrom, produced by this mounding on the 20 floor, are thus entirely eliminated. In so far as the shale lies on the floor of the retort at all in cases where the speed of rotation is very slow it is found to lie in a smooth even layer as showered from the back portion of 25 the shovels.

As one means of preventing the mixing 30 of the gases evolved in the various zones of the furnace there may be provided partitions 28 for separating the zones, each of the partitions being provided with openings 29 for the shaft 10, the openings being just sufficient in size to permit the insertion 35 of the shaft so that the shaft will close the openings. The partitions extend to the desired distance from the bottom of the retort, leaving a space beneath the partitions sufficient for the passage thereunder of the shale which is being moved through the retort but otherwise closing the retort between 40 the zones. It will be evident that these partitions will prevent the mixing of the gases evolved in one zone with those evolved in another so that the gas evolved in each zone will pass off through the vent from that 45 zone.

Modifications in the proportions, numbers of shovels, form and means for adjusting the guides, etc., will readily suggest them-

selves to the minds of those skilled in the art.

What I claim is:

1. In a retort for treating shale and the like, having a bottom, a plurality of shovels adapted to sweep successive zones of the retort, means carried by each of the shovels 55 adapted to deflect material therefrom into the zone swept by the next adjacent shovel, comprising an adjustable side guide.

2. In a retort for treating shale and the like, means for showering and advancing 60 the shale through the retort comprising a plurality of shovels adapted to sweep successive and adjacent zones of the retort, each shovel comprising a bottom inclined backwardly and upwardly from its forward 65 edge at an angle to the floor of the retort and having an adjustable side guide adapted to deflect the material from each shovel into the zone of the next adjacent shovel.

3. In a retort for treating shale and the like, means for showering and advancing the shale through the retort comprising a plurality of shovels adapted to sweep successive and adjacent zones of the retort, each shovel comprising a bottom inclined backwardly and upwardly from its forward edge 70 at an angle with the floor of the retort, an adjustable side guide adapted to deflect the material from each shovel into the zone of the next adjacent shovel, and means for 75 yieldingly maintaining the forward edges of the shovels in contact with the floor of the retort.

4. In a retort for extracting oils from shale, a shovel having side flanges to guide 80 the shale on the shovel, and means for advancing the shovel with its bottom at an acute angle relative to the floor of the retort with its front edge in yielding contact therewith, whereby the shale is carried up 85 the inclination of said shovel and showered or cascaded over its back edge to one side.

In testimony whereof I affix my signature.

JOSEPH H. GINET.
